UNITED STATES PATENT OFFICE.

WILLIAM O. PEAVEY, OF EBRO, MINNESOTA.

POST-PEELING MACHINE.

1,284,760.

Specification of Letters Patent. Patented Nov. 12, 1918.

Application filed April 10, 1918. Serial No. 227,725.

To all whom it may concern:

Be it known that I, WILLIAM O. PEAVEY, a citizen of the United States, residing at Ebro, in the county of Clearwater and State 5 of Minnesota, have invented certain new and useful Improvements in Post-Peeling Machines; and I do hereby declare the following to be a full, clear, and exact description of the invention, such as will enable others 10 skilled in the art to which it appertains to make and use the same.

This invention relates to improvements in post or mine stock or timber peeling machines and has for one of its objects the 15 provision of a device of this character whereby the bark of a log may be readily removed by rotating knives and which knives are capable of adjustment to accommodate logs of different sizes.

20 Another object of this invention is the provision of means for guiding the posts to the knives so that they will be in proper position when coming in contact with the knives.

25 A further object of this invention is the provision of the cutting means or knives located in upper and lower pairs and which upper pair is supported in a swinging structure so that the upper pair can readily adjust itself to the post and which is located 30 in rear of the lower pair, whereby one-half of the bark of the post is removed in advance of the other half.

35 A still further object of this invention is the provision of a log peeling machine of the above stated character, which will be simple, durable and efficient, and which may be manufactured and sold at a comparatively low cost.

40 With these and other objects in view, as will become more apparent as the description proceeds, the invention consists in certain novel features of construction, combination and arrangement of parts as will be hereinafter more fully described and claimed.

45 For a complete understanding of my invention, reference is to be had to the following description and accompanying drawings, in which:

Figure 1 is a longitudinal sectional view of the post peeling machine constructed in accordance with my invention.

Fig. 2 is a fragmentary sectional view illustrating the lower cutting means and the 55 post guide means associated therewith.

Fig. 3 is a fragmentary vertical sectional view illustrating the means of suspending the upper cutting means,

Fig. 4 is a detail sectional view illustrating the manner of supporting the guides.

Fig. 5 is a detail sectional view taken on the line 5—5 of Fig. 3 illustrating the means for permitting adjustment of the upper cutting means.

Referring in detail to the drawings, the numeral 1 indicates a table top supported by suitable legs 2 which are braced by members 3. The table top 1 is provided with a transverse opening 4 in which is mounted a transverse shaft 5. The shaft 5 is journaled in suitable bearings 6 carried by the table top 1 and has secured to one end a pulley 7 for the purpose of receiving an ordinary power belt. A pair of substantially frusto-conical blocks 8 are splined to the shaft 5 and have their walls concave, as clearly illustrated in Fig. 2. The blocks 8 have their apexes disposed in the direction of each other and are urged in the direction 70 of each other by means of expansion springs 9 mounted upon the shaft 5. The expansion springs 9 have one of their ends disposed against the blocks 8, while their opposite 75 ends bear against shoulders 10 formed upon the shaft, providing a construction wherein the blocks may move toward each other to accommodate logs of different sizes. The concave faces of the blocks 8 are provided

80 with grooves in which are positioned arcuate 80 shaped cutting knives 11, and which are secured therein by suitable fastening elements 12. The knives of one of the blocks are in a line with the knives of the other block so that they coöperate with each other in 85 forming substantially semi-circular cutting knives which will remove substantially one-half of the bark from a post 13 when it comes in contact with the same.

90 The table top 1 is provided with longi- 90

95

tudinally extending openings 14 that communicate with the transverse slot or opening 4 for the purpose of receiving spaced guide members 15 that are arranged in pairs upon each side of the blocks 8. The guide members 15 of each pair have their upper ends beveled in opposite directions, as illustrated at 16, for the purpose of engaging and conforming to the contour of the post. The guide members 15 are slidably supported in hangers or supporting members 17 that are secured to the under face of the table top 1 to connect with the openings 14. The hangers or supporting members 17 are divided into guideways 18 by means of partitions 19. Expansion springs 20 are located within the guideways 18 for the purpose of normally urging the guide members 15 upwardly into engagement with the post, but which permit the guide members to move downwardly within the hangers to accommodate themselves to different sizes of posts. The hangers or supporting members 17 have journaled therein transversely extending shafts 21 and the guide members 15 are provided with slots 25 to receive the shafts so that the guide members may move upwardly and downwardly without interfering with the shafts. The shafts 21 are also journaled to the table top 1 and disposed below the same and have mounted thereon feed rollers 22 which are disposed within the slots or openings 14 between the pairs of guide members 15. The feed rollers 22 have teeth or spikes 23 formed thereon for the purpose of biting into the post to feed the same across the table top 1 upon rotation thereof. One of the shafts 21 has a pulley 24 that receives a belt 25 that travels over a pulley 26 carried by the shaft 5, whereby upon rotation of the shaft 5, the said shaft 21 will be rotated therewith. The said shaft 21 also has a pulley 27 adjacent its opposite end on which a belt 28 travels. The belt 28 passes over a pulley 29 carried by the other shaft 21 so that the other shaft 21 is driven by the first named shaft 21. Upwardly inclined supporting members 30 are secured to one end of the table top 1 and have their upper ends disposed in vertical alinement with the shaft 5. The supporting members 30 carry at their upper ends cylindrical extensions 31 which have journaled thereon hanger arms 32. The hanger arms 32 are capable of swinging about the cylindrical extensions 31 and are retained thereon by means of nuts 33. A shaft 34 extends through the cylindrical extensions 31 and is rotatably supported by the supporting members 30. A belt 35 is connected to one end of the shaft 34 and to the shaft 5 for the purpose of rotating the shaft 34 with the shaft 5. The

hanger arms 32 adjacent their free ends are provided with slots 36 in which are slidably mounted bearings 37. The bearings 37 are provided with grooves 38 which receive ribs 39 formed on the walls of the slots 36 so that the bearings are held against lateral movement with relation to the hanger arms 32 but which permit the bearings to be moved upwardly and downwardly in relation to the arms 32. The bearings are held against accidental movement by means of bolts 40. The bearings 37 have journaled therein a shaft 41 on which are splined substantially frusto-conical shaped blocks 42 that are identical in construction with the blocks 8 and are each provided with cutting knives. The blocks 42 are urged in the direction of each other by means of expansion springs 43 mounted upon the shaft 41. The shaft 41 has a pulley 44 connected to one end over which travels a belt 45. The belt 45 extends over a pulley 46 secured to the shaft 34, whereby upon rotation of the shaft 34, the blocks 42 will be rotated thereby.

In operation, the upper cutting elements are supported in rear of the lower cutting elements as clearly illustrated in Fig. 1. The post 13 is fed onto the table top 1 and into engagement with the lower cutting elements first by one of the feed rollers 23 and as the same passes the lower cutting elements substantially one-half of the bark of the post is peeled or removed, and upon further movement of the post it moves into engagement with the upper cutting elements which rest thereon by gravitation and remove substantially the other half of the bark of the post. By having the upper cutting element mounted in the manner heretofore described, it permits the same to accommodate itself to posts of several sizes. The upper cutting element may also be adjusted upon the arms 32 by adjusting the location of the bearings 37 with relation thereto.

While I have shown and described the preferred embodiment of my invention, it will be understood that minor changes in construction, combination and arrangement of parts may be made without departing from the spirit and scope of the invention as claimed.

Having thus described my invention what I claim is:

1. A post peeling machine comprising a table, upper and lower cutting elements carried by said table, hangers carried by said table, spring actuating guide members carried by said hangers for guiding a post between the cutting elements, and means feeding the post between the cutting elements.
2. A post peeling machine comprising a

table, a shaft journaled to said table, substantially frusto-conical blocks splined to said shaft, means urging the blocks in the direction of each other, knives carried by the blocks, an upper cutting element carried by the table and capable of swinging movement to accommodate itself to posts of several sizes, and means feeding the post into

engagement with the knives and with the upper cutting element. 10

In testimony whereof I affix my signature in presence of two witnesses.

WILLIAM O. PEAVEY.
